UNITED STATES PATENT OFFICE

100,935

DESIGN FOR A SLIPPER OR SIMILAR ARTICLE

Jack Barnett, Brooklyn, N. Y.

Application June 15, 1936, Serial No. 63,311

Term of patent 3½ years

To all whom it may concern:

Be it known that I, Jack Barnett, a citizen of Russia, residing at Brooklyn, in the county of Kings, State of New York, have invented a new, original, and ornamental Design for a Slipper or Similar Article, of which the following is a specification, reference being had to the accompanying drawing, forming part thereof.

Fig. 1 is a plan view of a slipper showing my new design.

Fig. 2 is a perspective view thereof.

I claim:

The ornamental design for a slipper or similar article as shown.

JACK BARNETT.
